UNITED STATES PATENT OFFICE

1,981,115

VACUUM TUBE

Edmund Guyer Murphy, Chicago, Ill.

Application December 14, 1928, Serial No. 326,009

3 Claims. (Cl. 250—27.5)

This invention which relates to vacuum tubes or electron discharge devices is a continuation in part of and an improvement over the subject matter of my copending application, Serial No.

5 73,822, filed December 7, 1925, for Vacuum tubes and patented as Patent 1,699,011, Jan. 15, 1929.

The main object of the invention is to provide an improved vacuum tube with novel self-inclosed adjustable means whereby the tube may 10 be operated on those points of the locus of the characteristic curves thereof that will result in maximum circuit efficiency in radio transmitting and receiving.

Another object is to provide a vacuum tube 15 with adjustable insertable means for the variable control and regulation of the electrodes therein independently of external apparatus.

A further object is to provide a vacuum tube with self-inclosed adjustable means for varying 20 the potential or bias to be applied to the grid electrode of the tube.

More particular and special objects of the individual tubes and the various modifications herein disclosed will be set forth in separate 25 paragraphs in the details hereinafter set forth, reference being had to the accompanying drawings in which:

Figure 1 is a side elevation of a vacuum tube embodying my invention;

30 Fig. 2 is a vertical sectional view of Fig. 1;

Fig. 3 is a vertical sectional view of a slightly modified form of the tube shown in Fig. 2, illustrating the use of an insertable potentiometer for fine adjustment of potential to one of the 35 electrodes or for stabilizing the circuit;

Fig. 4 is a diagrammatic view of the circuit embodied in the tube shown in Fig. 3;

Fig. 5 is an enlarged longitudinal sectional view of one of the insertable cartridge resistance 40 units;

Fig. 6 is a modification of the form shown in Fig. 3;

Fig. 7 is a modified form of the invention showing the control of the grid electrode by a 45 combination cartridge condenser and grid leak;

Fig. 8 is a modification of the form of the invention shown in Fig. 2, with insertable means for varying the output impedance of the tube;

Fig. 9 is a combination tube showing adjustable insertable means for varying the output impedance of the tube, and a fixed value insertable cartridge resistance unit for the control of the filament;

50 Fig. 10 is an enlarged longitudinal sectional view of a combination cartridge condenser and

grid leak employed in the tube illustrated in Fig. 7;

Fig. 11 is a transverse section taken on line 11—11 of Fig. 10;

Fig. 12 is an enlarged longitudinal sectional view of a fixed value cartridge resistance unit 60 employed in the tube illustrated in Fig. 9;

Fig. 13 is an elevational view of the exterior of a modified form of tube showing an enlarged base for the reception of heavy duty cartridge 65 units; and

Fig. 14 is a longitudinal sectional view of a cartridge potentiometer unit as employed in the tubes shown in Figs. 3, 4 and 6.

In the drawings wherein similar characters of 70 reference indicate corresponding parts in the several views of the preferred forms of my invention, A designates a glass envelope secured to a base B having a subsocket 15 to be described more fully elsewhere in the present specification. Formed integrally with the envelope is 75 the press 16 in which are imbedded the supporting rod 17 for the cathode 18, the rod 19 for the grid 20, and the rod 21 supporting the anode or plate 22.

In the construction shown in Figs. 1 and 2, one of the electrodes, in this instance the filament, is variably controlled by the insertable cartridge resistance unit C which is clampingly held in the socket members 23, 24 which are 85 formed of short sections of split metal tubing crimped to opposite sides of the wall of the base.

To the bottom of the base B of the tube are secured the circuit-completing prongs which 90 include the filament prongs 25, 26; the grid prong 27 which is connected to the grid electrode by wire 28, and the anode prong 29 which is connected to the anode by lead 30. By inspection of Fig. 2, it will be seen that filament prong 26 is connected by wire 31 to right hand socket member 24 whence the filament circuit 95 may be completed through the cartridge element C which may be slid transversely of the arm 32 secured on the inner bottom of the base of the tube, the arm contacting with resistance winding 33, whereby the resistance and consequently the current fed to the filament 18 via lead 34 attached to arm 32, may be varied.

The resistance cartridge unit C which is employed in the tube shown in Figs. 1 and 2, is shown in detail in Fig. 5. It consists of a tube 35 of glass or other suitable insulating material closed at each end by caps 36, 37 containing plugs of fusible metal 38, 39 connected 100 to the filament 18 and the grid 27. The tube 35 is 105 secured in the base B of the tube by means of a 110

by a metal fuse strip 40 of a resistance value suitable to the filament employed. Wound upon the exterior of the tube 35 is the inductive resistance 33 which is connected at one end to cap 36. It will be seen from the above description that filament 18 may be variably regulated and at the same time safeguarded against excessive applications of current by the fuse 40. Should the fuse melt, thus breaking the circuit and preventing the destruction of the filament, another cartridge resistance may be inserted. The tube may also be operated in its conventional capacity by merely thrusting a short section of metal rod of suitable size into the subsocket 15 in place of cartridge unit C. The provision of a fuse in the cartridge element C is particularly valuable in the case of power and transmitting tubes wherein the destruction of the filament is a costly matter as the tube is thereby in most cases rendered worthless. The filament circuit of the tube shown in Figs. 1 and 2 is energized from prong 25, wire 25', rod 17, filament 18, lead 34, arm 32, winding 33, cap 36, metal plug 38, fuse 40, metal plug 39, metal cap 37, socket member 24, wire 31 and prong 26 to battery D or other source of electrical energy.

In the modification shown in Fig. 3, the circuit of which is shown in Fig. 4, the filament circuit is shunted by an insertable potentiometer unit in the form of the cartridge E, the winding of which may be connected to the plate or grid electrodes through the arm 32. The potentiometer E is shown in detail in Fig. 14 and comprises a section of dielectric tubing 41 closed at each end by caps 42, 43 connected by the exterior inductive winding 44 which latter may be of any suitable ohmic resistance. In this respect, I have found the use of nichrome wire in practice to offer certain advantages as a winding for the potentiometer since its resistance is high enough to permit the use of a comparatively few turns of wire in order to obtain the desired resistance value. A fifth prong 45 in the tube illustrated in Fig. 3, may be outwardly connected to the positive or negative of the source of plate energization, in this manner a fine adjustment of the filament-plate potential may be obtained. This feature is especially desirable in thermionic detectors and particularly so in "soft" or gaseous thermionic valves which are exceedingly sensitive and responsive to slight variations of potential. It will be apparent from inspection of Fig. 4 that the grid return can be applied to the positive or negative side of the filament battery and that consequently the grid bias can be graduated finely between positive and negative values. In Fig. 4, by way of example, both the plate and the grid are connected to the potentiometer, but it will be obvious that either the grid return singly or the plate return singly may be applied to the positive or negative side of the filament battery or other source of power through one of the prongs 25, 26,—if desired. The filament circuit of the tube shown in Fig. 3, and diagrammatically shown in Fig. 4, is completed from the prong 25, wire 25', rod 17, filament 18, lead 34' to prong 26,—wire 25' and lead 34 being also connected to socket members 23, 24 between which the potentiometer E is secured,—this potentiometer as illustrated diagrammatically in Fig. 4 permitting or shunting a part of the filament current to flow through the winding 44 which in this instance, as indicated above, may be of compara-

tively high resistance. When the fifth prong 45 which is connected to arm 32 is attached to one of the poles of the source of plate energization, in this instance the negative pole being employed, it will be apparent that by sliding the member E a greater or less number of windings of the resistance 44 will be introduced between the positive or negative side of the battery 42, the maximum variation possible being the difference of potential between the poles of the filament battery D.

Fig. 6 illustrates a tube of practically the same description as that shown in Fig. 3 except that the fifth prong has been eliminated and a binding post 46 substituted,—the wiring connections in the interior of the base otherwise being identically the same. Where it is not desired to employ five prong tubes, this form offers an alternative.

In Fig. 7, a combination cartridge grid leak and condenser F is shown which is inserted between the socket members 23 and 24 in series with the grid electrode of the tube which may be of the usual conventional structure so far as the disposition of the envelope, press and electrodes is concerned. The element F, as shown in Fig. 10, comprises a tube of dielectric 47 having an inner coating 48 of high resistance metal serving as an electrode grid leak. The leak resistance 48 may either be sputtered on the inner wall of the glass tube 47, or it may be cast with the glass as one of the ingredients of the latter,—a number of metallic salts in suitable proportion with the other well known ingredients of glass answering the purpose indicated. A metal plug 49 of fusible metal closing one end of the tube is connected to the ends of a number of separated sheets of metal or foil 50 insulated, one from the other by sheets of paraffined paper 51,—these sheets of metal being separated by the paper sheets from other sheets or metal or foil 52, the latter being attached to the opposite metal plug 53. The metal plugs 49 and 53 are in contact with the electron leak resistance 48 which is chosen of suitable value and preferably between the usual limits of 10⁵ and 10⁷ ohms. Metal caps 54 and 55 at either end of the tubing 47 complete this combination grid leak and condenser which as a cartridge may be inserted in the subsocket 15 of the tube shown in Fig. 7. The grid circuit may now be energized from prong 27, lead 28', socket member 24, cap 55, metal plug 53, through leak resistance 48 and electrostatically through the sheets 50 and 52 of the condenser element, metal plug 49, cap 54, socket member 23, to lead 28 and grid 20.

Fig. 8 in its construction, is based substantially on the form of tube shown in Figs. 1 and 2,—the cartridge unit C in this modification being inserted in the subsocket 15 in series with the plate electrode 22 whereby the plate or output impedance of the tube may be equalized with the load resistance. As is well known to those skilled in this art, the power output of a thermionic valve is greatest when the plate impedance of the tube or valve is made substantially equal to the load resistance. It is also to be noted that in all forms of receiving sets employing vacuum tubes, and particularly those circuits employing high frequency oscillation transformers the electrical constants of which are of uniform value, the use of thermionic valves of substantially the same output impedance is imperative if the maximum possibilities

or efficiency of the circuit is to be realized. As indicated in Fig. 8, the plate impedance of a series of thermionic valves can be "matched", one with the other, assuming the tubes to be 5 of the same type and average capacity. The circuit of this tube, as illustrated in Fig. 8, so far as the plate circuit is concerned, is completed from prong 29 to clamping socket member 24, cap 37, metal plug 39, resistance strip 40, metal 10 plug 38, cap 36, winding 33, arm 32, lead 22' to anode 22.

Fig. 9 shows a modification embodying a combination of means for controlling the output impedance of the tube and for regulating the 15 filament circuit. The plate circuit of this tube is completed from anode plate 22, wire 32' to socket member 56, cap 37, metal plug 39, resistance strip 40, metal plug 38, metal cap 36, winding 33 and contact arm 57 to prong 29. 20 The means for regulating the filament circuit comprises a fixed value resistance unit G, shown in Fig. 12, which is placed in series with the filament. The unit G consists of a section of dielectric tubing 58, closed by metal caps 59, 60 which inclose plugs of fusible metal 61, 62 in which are imbedded the ends of the winding 63 which, in this modification is within the interior of the tubing 58. When the cartridge unit G is placed in the socket members 23, 24, the 25 filament circuit may now be completed from prong 26, socket member 24, cap 60 of element G, metal plug 62, winding 63, metal plug 61, cap 59, lead 64, filament 18, rod 17, wire 25' to prong 25.

30 In Fig. 13, a tube is shown wherein the base is enlarged to accommodate comparatively large or heavy-duty cartridge units. The prongs and the immediate lower part of the adjoining bottom of the base of this tube, however, is of conventional construction so that it may be received by any of the standard tube sockets.

If alternating current is employed to energize the filament and plate circuits of these tubes, the modification shown in Fig. 3 is particularly 45 desirable as the objectionable hum especially noticeable in low-voltage alternating current circuits when connected to sound reproducing means,—can be almost completely eliminated. This is accomplished by inserting a cartridge resistance element E in the subsocket 15 and then applying a positive potential from the plate energizing source. In this instance, it is assumed that a separate insulated cathode of conventional type is employed in addition to the heating filament. The grid bias in the alternating current 55 type of thermionic valves is, of course, obtained from the alternating current plate current supply by inserting a cartridge resistance of suitable value between the negative pole and positive 60 pole of the filament energizing source and then connecting the grid and plate electrodes as shown in Fig. 4. The correct value of the

resistance required is deduced from the IR drop across this resistance, the grid bias required being known from the characteristics of the particular tube, assuming definite plate potentials.

It will be apparent from the foregoing description and illustrations that the invention lends itself to the widest modification and change, and it is accordingly to be understood that the types described are merely representative; hence, I do not confine myself to the details precisely as set forth but desire to avail myself of such variations and embodiments as fairly fall within the limits of the appended claims.

What I claim as new and desire to secure by Letters Patent is:

1. In combination, an electron discharge device having filament, grid and plate electrodes in an envelope, a base secured to said envelope and means removably insertable in the base including a manually adjustable cartridge potentiometer element electrically connected to the ends of one of said electrodes and to at least one other of said electrodes, whereby when said potentiometer element is moved relatively to a contact connected to one of the electrodes, the filament-plate potential may be varied and simultaneously therewith a variable positive and negative potential selectively applied to the grid electrode.

2. An electron discharge device suitable for alternating current energization comprising an envelope having a plurality of electrodes mounted therein, a base secured to said envelope, circuit completing prongs attached to the base, and means insertable in said base for making operative the electron discharge device, said means including a cartridge inductance movable transversely of a contact member secured within the base and electrically connected to at least one of the electrodes, for negatively and positively biasing, optionally as desired one of the electrodes and varying the potential gradient along another of said electrodes, said prongs being electrically connected to said electrodes.

3. In combination, an electron-discharge device having a plurality of electrodes fastened in an envelope directly secured to mechanical means, an arm secured to said means, a tubular potentiometer slidably engageable with said arm, a pair of clamping members electrically connected to at least one of the electrodes and operative to receive said potentiometer within the said means, and external means for electrically connecting the arm to the potentiometer and thereby to at least one of the said electrodes for optionally applying and carrying a positive and negative potential to another of said electrodes.

EDMUND GUYER MURPHY. 135
